UNITED STATES PATENT OFFICE.

WILHELM RABUS, OF HEIDENHEIM-ON-THE-BRENZ, GERMANY, ASSIGNOR TO AMERICAN VOITH CONTACT COMPANY, INC., OF NEW YORK, N. Y., A CORPORATION OF NEW YORK.

APPARATUS FOR FEEDING CONTINUOUS-WORKING WOOD GRINDERS AND METHOD THEREOF.

Application filed September 3, 1924, Serial No. 735,552, and in Germany September 16, 1923.

This invention relates to apparatus for feeding continuous working wood grinders of the type generally known as magazine grinders, and has for its object to provide an improved apparatus in which the charge is subjected to pressure in the immediate proximity of the grindstone, and at the same time that portion of the charge is caused to be compressed to a greater degree than in the remaining portions of the magazine or hopper, in which the charge is moved stoneward.

The invention has for its object to provide improvements over the structures and methods disclosed in my co-pending application Serial No. 720,422, filed by me in the U. S. Patent Office on June 14, 1924, Patent No. 1,532,946 for an apparatus for feeding continuous working wood grinders and methods thereof. In that application the invention therein claimed consists, among other things, of the arrangement of toothed wheels entering into the magazine or hopper in proximity to the grindstone, the teeth or projections of said wheels serving to move the wood toward the grindstone at the same time that a special compression of the charge in proximity to the grindstone is obtained. The present invention comprises members entering into the magazine in proximity to the grindstone and providing such members with gaps therebetween for collecting therein the logs of the charge, the so-collected logs being guided in said gaps between said members and the members themselves serving to press the logs directly against the grindstone. Such members may be arranged in different ways and modified within the spirit of my invention, and various embodiments thereof are shown and described hereinafter.

The invention will be more fully shown in the accompanying drawings and hereinafter described, and finally pointed out in the claims.

In the accompanying drawings,—

Figure 1 is a vertical central section of a well-known magazine grinder to which is applied one embodiment of my invention;

Figure 2 is a similar section to which is applied another embodiment of my invention,

Figure 3 is a partial detail view of still another embodiment of my invention,

Fig. 4 is a vertical central section of the

magazine grinder shown in Fig. 1 with parts thereof in a changed relation, and

Fig. 5 is a similar section to that shown in Fig. 4 of the embodiment disclosed in Fig. 2.

Similar characters of reference indicate corresponding parts throughout the various views.

Referring to the drawings, and more particularly to Fig. 1, the well known magazine grinder containing a charge is therein shown, being indicated by C. Along the walls of this magazine at the lower portion thereof and in proximity to the grindstone B openings F are provided into which openings preferably at both sides of the magazine, members A intrude. These members A are in the nature of wheels rotating on shafts A'. Along the periphery of said rotating members A, separating members G are provided, between which members G gaps H are formed. The members G are inclined to the radii of the rotary members A and walls T connect the members G, these walls T being preferably curved in shape. The disposition of the members G and the gaps H and the walls T are such that when these members enter into the magazine to their fullest extent, the walls T are in substantial alignment with the inner surface C¹ of the magazine. The members G are so disposed in respect to the rotary supporting members A that the gaps H are presented in their open position to the charge of the grindstone as the members G approach the grindstone and by reason of this, certain logs of the charge in the magazine drop into the gaps H. In Figure 1 these certain logs are indicated by the character L. The limitation imposed upon the position of these logs L that so enter the gaps H, is the inside surface C¹ of the magazine C. As the members A rotate they serve to carry with them the entrained or captivated logs and as the members G pass out of the opening F in the walls of the magazine C, the walls of the magazine serve to prevent the logs from following the movement of the members G and the gaps H therebetween and the members G serve to press the logs L downwardly against the grindstone, at the same time compressing the adjacent logs or the logs intermediate the logs pressed by the members G and those in direct contact with the grind-

95

110

stone. The members G thereby serve to give a special pressure against the logs and compress the adjacent logs and in fact, all those in proximity to the grindstone. Preferably these pressure plates G are arranged tangential or substantially so in respect to the periphery of the wheels or members A. They are disposed at such a distance from each other that between each pair a sharp angled gap which is preferably rounded at its bottom, is arranged in a manner specially adapted to the collecting and guiding of the logs as they fall into such gaps from above. As these pressure plates G continue to enter into the magazine, they proximate more and more the horizontal, and by this serve, in this manner, to subject the logs under such pressure plates to pressure and press and compress them against the grindstone B. When such pressure plates come nearest to the grindstone they again are withdrawn out of the charge.

In the embodiment shown in Figure 2, instead of having the pressure plates firmly secured to the wheel as in Figure 1, these pressure plates may be suitably linked to the wheel and also provided with spring actuated means to give a certain flexibility of movement thereto. For this purpose, the pressure plates G¹ are pivoted at G² to the wheel and between the wheel and the pressure plates G¹ suitable springs e³ are arranged. The peripheral portion of the wheel itself is provided with abutment portions e² on the wheel E which enter somewhat into the interior of the magazine, and serve at the same time to prevent the logs from coming in direct contact with the springs. Suitable mechanical devices as covering plates for the springs can, of course, be arranged and preferably, of course, these springs are of such a character that they prevent too much of a movement of the pressure plates G¹ away from the periphery of the wheel E, though here also suitable mechanism may be provided to limit the movement of the plates G¹. In the drawings, such means are shown in that the rear end of the pressure plates G¹ abut against the abutment e¹ whereby their movement is limited. Again between the pressure plates G¹ the gaps or pockets H' are formed which receive the logs as they enter into the magazine and convey them by the logs resting on one side of said pressure plates, and press the logs downwardly against the grindstone by the other side of the pressure plates exerting a compressing action on the logs in the direction of the grindstone. The relative movement of these pivoted pressure members G¹ particularly when under spring tension, gives a certain flexibility of movement thereto. The shafts A¹ and E¹ of the embodiments shown in Figures 1 and 2, may be suitably adjusted by means of screw spindles b¹.

65 In Figure 3 I have shown another embodi-

ment of the pressure plates corresponding closely to the paddle wheels of paddle steamers and it is of course, clear that these pressure plates may be arranged with any suitable mechanical, hydraulic, pneumatic or electrical steering device which would adjust and regulate the position of the pressure plates in their path from the entrance into the magazine to their exit therefrom.

Preferably, as shown in Figs. 4 and 5, the pressure plate wheels are so arranged in respect to the charge on the grindstone, that they are disposed in respect to each other, in a manner that the end of one pressure plate on one wheel is in line with the gap between two pressure plates on the other wheel. The construction of the two members is the same as those shown in Figs. 1 and 2, but the wheels A and wheels E are turned with respect to each other as just stated. This arrangement has certain advantages in that greater flexibility results since the direct horizontal pressure resulting from two pressure plates being on the same horizontal line is thereby avoided and a corresponding jamming is obviated, with the result that the logs can more readily fall into the pockets or gaps.

Among the advantages of the described arrangements in respect to the prior devices, is that in consequence of the continual change of position of the pressure plates in respect to the charge of the logs thereof, the pressure plates on the one hand permit the dropping of the logs of the charge into the gaps or pockets formed between the pressure plates, and that taken on the other hand in the course of their continual progressive movement corresponding to the revolution of the wheels, positions particularly advantageous in that they provide a relatively lateral as well as a downwardly directed compression of the charge in the proximity of the grindstone and in the direction towards the grinding surfaces of the grindstone. At the same time the exit of the pressure plates out of the charge of the magazine in very close proximity to the grindstone takes place essentially in the direction of their own surfaces so that by their exit the least amount of resistance is encountered during their withdrawal. The withdrawal of the pressure plates in the line of their own surfaces may thereby, be readily accomplished without subjecting the discharge to any disturbing influences.

120 A further advantage of the embodiments described and particularly so when the pressure plates are pivoted or hinged, is that within certain limits, the pressure plates may adapt themselves to the particular shapes of the individual logs comprising the charge, these logs, as is well known, having different shapes and dimensions. When the pressure plates are arranged so that the pressure plates of the opposite wheels are stag-

gered to each other, a further advantage is presented in this that the downward produced resulting pressures from the alternating downward left movement and downward

5 right movement, very favorably influence a tight and closed position of the individual logs directly over the grindstone.

It will also be noted that the pressure members on the rotary members extend only partially within the charge, that is, they do not extend beyond the median line thereof, and preferably such rotary members engage only the lateral sides of the charge at opposite sides thereof.

15 The improved method consists in separating certain logs of the charge during their movement toward the grindstone and then subjecting the separated logs to a special downward or stoneward pressure and the 20 improved method consists further in subjecting a charge of a magazine grinder alternately to the right and to the left of laterally inward and stoneward pressures.

I have described several embodiments of 25 my invention and have shown them in the accompanying drawings, and have also described a method for the grinding of logs, but I do not wish to be limited to the details thereof, as do not enter into the spirit of 30 my invention as defined in the following claims.

What I claim as new is:

1. Apparatus for feeding wood grinders comprising a magazine for receiving a charge 35 of logs, a grindstone cooperating with said magazine, and means for compressing the wood charge directly toward the grindstone, said means comprising rotary members having pressure plates extending tangentially 40 outward therefrom entering into and passing into the magazine under rotary movement for collecting certain logs of the charge between successive plates and pressing them toward the grindstone, said pressure member entering 45 beyond the lateral side of the magazine and into the charge and within the median line of the charge and such pressure means further keeping the charge away from the magazine walls so as to avoid friction between 50 the charge and the walls.

2. Apparatus for feeding wood grinders comprising a magazine for receiving a charge of logs, a grindstone cooperating with the magazine, and means for compressing the wood charge directly toward the grindstone, said means comprising rotary members having pressure plates extending tangentially outward therefrom forming pockets therebetween, entering into and passing into the magazine under rotary movement for collecting certain logs of the charge between successive plates and pressing them toward the grindstone, said pressure means entering beyond the lateral side of the magazine and into 65 the charge and within the median line of the

charge and such pressure means further keeping the charge away from the magazine walls so as to avoid friction between the charge and the walls.

3. Apparatus for feeding wood grinders 70 comprising a magazine to receive a charge of logs, a grindstone to cooperate with the magazine, and means for compressing the wood charge directly toward the grindstone, said means comprising rotary members having 75 pressure plates extending tangentially outward therefrom forming pockets therebetween, entering into and passing into the magazine under rotary movement for collecting certain logs of the charge and pressing 80 them toward the grindstone, the said pressure plates and pockets being so disposed that they first enter into and as they pass through the magazine are withdrawn from the logs, said pressure member entering beyond the 85 lateral side of the magazine and into the charge and within the median line of the charge and such pressure means further keeping the charge away from the magazine walls so as to avoid friction between the charge 90 and the walls.

4. Apparatus for feeding wood grinders comprising a magazine to receive a charge of logs, a grindstone to cooperate with said magazine, and means for compressing the 95 wood charge directly toward the grindstone, said means comprising rotary members having pressure plates extending tangentially outward therefrom forming pockets therebetween, entering into and passing through 100 the magazine under rotary movement for collecting certain logs of the charge and pressing them toward the grindstone, the said pressure members and pockets being so disposed that they first enter into and as they 105 pass into the magazine are withdrawn from the logs and plates and being so disposed that they take substantially horizontal position as they withdraw from the charge of the magazine.

5. Apparatus for feeding wood grinders comprising a magazine to receive a charge of logs, a grindstone to cooperate with the magazine, and means for compressing the wood charge directly toward the grindstone, said 110 means comprising rotary members having pressure plates extending tangentially outward therefrom, entering into and passing into the magazine under rotary movement for collecting certain logs of the charge and pressing them toward the grindstone, said plates entering only the lateral sides of the charge at opposite sides thereof, without extending beyond the median line thereof, said means, after having entered the walls of the magazine gradually being projected more and more into the charge up to a maximum projection thereafter being gradually withdrawn as the charge approaches the stone.

6. An apparatus for feeding continuous 130

working wood grinders which consists of a hopper or magazine having lateral openings, rotary members one at each of two opposite sides of the magazine or hopper, pressure plates arranged tangentially on said rotary members forming gaps or pockets therebetween, the opposite rotary members being so disposed that one pressure plate of one rotary member is aligned with the gap or pocket between two pressure plates of the opposite rotary member.

7. An apparatus for feeding continuous working wood grinders which consists of a hopper or magazine having lateral openings, rotary members one at each of two opposite sides of the magazine or hopper, pivoted pressure plates on said rotary members forming gaps or pockets therebetween, the opposite rotary members being so disposed that one pressure plate of one rotary member is aligned with the gap or pocket between two pressure plates of the opposite rotary member.

8. An apparatus for feeding continuous working wood grinders which consists of a hopper or magazine having lateral openings, rotary members one at each of two opposite sides of the magazine or hopper, pivoted and spring actuated pressure plates on said rotary members forming gaps or pockets therebetween, the opposite rotary members being so disposed that one pressure plate of one rotary member is aligned with the gap or pocket between two pressure plates of the opposite rotary member.

9. Steps in the method of grinding materials, consisting in continuously feeding the materials as a column against the edge of a rotating grindstone, and imposing pressure of the materials against the grindstone on lines oblique to the direction of movement of the column and alternately from opposite sides thereof and toward the central portion of the operative zone of the grindstone periphery.

10. Steps in the method of grinding materials, consisting in continuously feeding the materials downwardly as a column against the edge of a rotating grindstone, and alternately imposing pressure on the opposite sides of the column adjacent the grindstone on lines oblique to the direction of movement of the column and toward the central portion of the operative zone of the grindstone periphery.

11. Apparatus for feeding wood grinders comprising a magazine and a grindstone to cooperate therewith, and means for compressing a charge of logs in said magazine towards the grindstone, said means comprising rotary members carrying pressure members on their peripheries to enter the magazine from opposite sides and collect the logs adjacent the grindstone to press them towards the latter; said rotary members being so disposed that the pressure members thereon enter the mass of said logs and force them away from the sides of the magazine adjacent the grindstone.

12. The method of grinding materials which consists in confining materials and in feeding them under the action of a force against a moving abrading member, and as said materials pass towards said member subjecting the mass thereof to pressure from opposite sides to compress the materials into a mass and towards the abrading member.

13. The method of grinding materials which consists in confining said materials and subjecting them to the action of a force to carry them in a mass against a movable abrading member and as the materials move towards the said member subjecting them to the action of pressure inward of the said mass and towards the said member alternately from opposite sides of said mass.

In testimony that I claim the foregoing as my invention, I have signed my name hereto.

WILHELM RABUS.
